H. P. K. Peck.

United States Patent Office.

A. E. HARDING, OF MIDDLETOWN, OHIO, ASSIGNOR TO HARDING, ERWIN, AND COMPANY, OF SAME PLACE.

Letters Patent No. 86,666, dated February 9, 1869.

IMPROVED APPARATUS FOR DRYING PAPER

The Schedule referred to in these Letters Patent and making part of the same.

To all whom it may concern:

Be it known that I, A. E. HARDING, of Middletown, in the county of Butler, in the State of Ohio, have invented certain new and useful Improvements in Apparatus for Drying Writing-Paper; and I do hereby declare that the following is a full and exact description thereof, reference being had to the accompanying drawings, and to the letters of reference marked thereon.

Figure 1 represents a vertical transverse section of a paper-drying house, with a blower, hot-air chamber, or drum, and a furnace, taken at the line *z z*, fig. 5.

Figure 2 represents a vertical longitudinal section of a drying-house, exhibiting one of the interior series of ventilating-flues, taken at the line *x x*, fig. 5.

Figure 3 represents an end view of the drying-house, with the furnace-door and smoke-flues.

Figure 4 is a perspective view of portions of the air-distributing tubes, with their adjustable gates, for the admission of hot air to the drying-lofts.

Figure 5 represents a horizontal section of the second story of the drying-house, taken at the line *y y*, fig. 1.

My invention relates to a new method of drying writing-paper, by artificial means, in a more perfect, economical, and expeditious manner than it has hitherto been accomplished.

It is well known to those familiar with the art of manufacturing writing-paper that such paper, being prepared with "animal-sizing," is subject to injury in drying. This frequently occurs from several causes, such as sultry, damp weather, continued exposure in a humid, heated atmosphere for an undue period of time, and from inequality of heat and circulation of air in the drying-lofts or chambers.

The object of my invention is to overcome these causes of damage and injury, by providing efficient means of controlling the temperature, quality, and quantity, as well as the circulation, of the air admitted into the drying-chambers.

My improved apparatus will cause uniformity of temperature, and constant, thorough diffusion of the volume of air continuously passing through the drying-lofts, thereby drying the paper in a uniform and expeditious manner.

These results could not be obtained by the use of steam-heated pipes, arranged within the lofts, as has hitherto been the practice, for the reason that there were no effectual means of discharging the humid hot air from the drying-lofts, nor any provision for producing positive action and circulation of dry, heated air among the folds of hanging paper.

The effect of this former method was the destruction of the "animal-sizing" by humidity, cold, or heat, and stagnation of vapors enveloping the paper.

In the accompanying drawings—

A B C denote the three stories of a drying-house. The furnace D, within the air-drum E, is connected

with chimney F by the pipe G, and the mouth of the furnace D is at the exterior of the house, as represented in fig. 3.

The blower, which consists of a drum, with a shaft and fans, is connected, at the bottom, with the bottom of drum E, by the rectangular box I, which serves as an induction-air tube.

Upon the second and third floors, the distributing-tubes are arranged, as represented in fig. 5.

These tubes are connected, by tubes *b*, with the hot-air drum E, at the openings, *c d*, therein.

The dampers *e f g* are provided for regulating the admission of hot air to the tubes *a a*, and thence into the chambers, or either of them; also for closing off the admission, as may be required, from time to time.

There are six ventilating-flues, M, which extend from the second floor to some distance above the house, and each of them may be provided with one or two adjustable sliding doors, N, for the emission of the air.

The distributing-tubes *a a* are provided with double series of adjustable sliding doors, *o o'*, arranged along the sides of the tubes, to regulate and control the admission of air into the drying-lofts.

The currents of air forced through at the doors *o* and *o'* cause a thorough diffusion of heated air throughout the lofts, and the attendant will be able to regulate and control these currents, by means of the slides or doors, so as to direct a greater or less volume of air to any part of the lofts or chambers where it may be necessary to accelerate the drying.

The paper to be dried is hung upon bars, arranged in suitable frames, and several sheets or thicknesses of the paper, one upon another, in close contact, constituting folios, fill the entire chamber.

The gates N may be arranged near the floors, or at any elevation, in the ventilating-flues M, to draw off the air, which will descend along the walls, after being charged with humidity, in passing up among the folds of damp paper.

It will be observed that the dampers *e f g* may be adjusted so as to direct the entire volume and current of air generated by the blower H into either of the drying-lofts, and that the adjustment of the sliding doors *o o'* may be such as to force the currents of air to any particular locality within the chambers or lofts.

The end of the fan-shaft of the blower may be provided with several pulleys, of differing sizes, by which means different degrees of speed may be given to the fan by a driving-belt, and thereby the volume of air and quantity of heat a given body of air will convey may be varied and changed at the pleasure of the attendant.

From the foregoing description, it will be apparent that the air forced by the blower through the drum E, surrounding the heated furnace, will be heated, and, in that condition, will enter the distributing-tubes *a a*, and will issue through the openings at *o o'*, forming

currents and counter-currents, which will produce a general diffusion of the dry, heated air throughout the chambers in which the paper is suspended, and, when it becomes laden with vapor thrown off by the drying paper, it will be forced off through the ventilating-flues, as hereinbefore described.

Having fully described my apparatus for drying writing-paper,

What I claim as my invention, and desire to secure by Letters Patent, is—

The combination of a blower, furnace, air-drum, distributing-tubes, ventilating-flues, and adjustable damp-

ers and doors, connected and arranged in such a manner as to force a volume of heated air through the drying-lofts, and to diffuse, regulate, and control the quantity, temperature, and circulation thereof, substantially in the manner and for the purpose described.

In testimony whereof, I have hereunto set my hand, this 18th day of December, 1868.

A. E. HARDING.
